UNITED STATES PATENT OFFICE.

AUGUST RIEBE, OF BERLIN, GERMANY, ASSIGNOR TO THE FIRM OF DEUTSCHE WAFFEN- & MUNITIONSFABRIKEN, OF BERLIN, GERMANY.

CASING FOR SHAFT-BEARINGS.

SPECIFICATION forming part of Letters Patent No. 687,404, dated November 23, 1901.

Application filed April 17, 1900. Serial No. 13,242. (No model.)

To all whom it may concern:

Be it known that I, AUGUST RIEBE, mechanical engineer, a subject of the King of Prussia, German Emperor, residing at 15^a Zwingli-5 strasse, Berlin, Kingdom of Prussia, German Empire, have invented certain new and useful Improvements in Casings for Shaft-Bearings; and I do hereby declare the following to be a full, clear, and exact description of the 10 invention, such as will enable others skilled in the art to which it appertains to make and use the same.

This invention relates to the construction of a folding casing for bearings, such as shaft-15 bearings, which can always be folded in the exact centering position in relation to the center of the shaft.

The invention consists in making the bearing-casing of clamps or segments suitably 20 hinged together and hinged to the base in order that when opened it may receive a suitable bearing-piece, which surrounds the shaft in the form of a bush and will enable this latter to be subsequently inclosed in a correct centering position with the assistance of 25 a screw and suitable stops. Each inserted bearing-piece may consist of bushes, as usual, with race-rings, or of a divided race-ring bush, which is arranged for adjustable ball 30 or roller bearings.

The novel construction of the bearing-casing is illustrated in the accompanying drawings.

Figures 1 and 2 are respectively a trans-35 verse and a longitudinal section of the same, while Fig. 3 is an external view of the casing in a partly-open position, Fig. 4 being an end view of the bearing in the closed position.

The construction of the bush *d*, which in 40 Fig. 3 is shown only in broken lines, is not essential for carrying out the present invention. The accurately-turned external surfaces of the piece or bush which has to be inclosed may be made spherical, in order that 45 the bearing may be mobile, in the manner of the Sellers bearing.

a is the casing-base, the given position of which determines the position of the axis of the shaft. The folding bearing-casing, which 50 is capable of being arranged on an invariable centering-line in relation to the base *a*, con-

sists of segmental clamps *p* and *q*, the former of which parts, *p*, can only turn on the hinge-bolt *b* in the base *a*, while the latter, *q*, is connected with the piece *p* by means of the 55 hinge-joint *r* and terminates in a slotted shoe-shaped piece to receive the fixing-screw *c* and having a shoulder or bearing *s* for the nuts to enable the piece *p* to be screwed to the base *a*. The said screw *c*, which is firmly 60 held by its prismatic head engaging in a hollow of the base *a*, runs through the slot in the shoe-shaped part of the piece *q*, so that after the nuts have been loosened it can be shifted and placed out of the range of the 65 piece *q*, which can then be turned outward. For the folded or closed position of the casing it is requisite that an extension of the piece *p* should rest against a stop *k*, Figs. 1 and 3, of the base *a*. The bearing-surfaces 70 for the inserted piece-bush are arranged concentrically at places in the pieces *p* *q* lying opposite to one another.

The casing constructed as above described is capable of being opened for the purpose of 75 cleaning the bush or adjusting it on the shaft *w*, and it secures the rearrangement of the bearing in the original centering position. The bearing can be opened by simply loosening the screw *c* in order to set the parts *p* *q* 80 free to be turned back, Fig. 3. In this manner the inserted bearing piece or bush is accessible for the purpose of being examined and relieved of any strain. When the adjustment has been effected and the bush runs 85 properly on the shaft *w*, the casing *p* *q* is folded down for the purpose of inclosing it, the nuts of the screw *c* being screwed tightly against the shoulder *s* of the piece *q*. The two clamps close in on the bush *d* and the 90 shaft *w*, and the latter is forcibly adjusted to the exact axial center, which is indicated in Fig. 3.

The bearing-casing may be furnished with holes in suitable places, as shown at *t*, Fig. 95 1, in order that the lubricating material may be able to flow readily to the interior bearing piece or bush.

What I claim is—

1. A casing for shaft-bearings consisting of 100 segmental clamps hinged together, a bearing-piece or race-ring bush, a base, a hinge-joint

connecting one end of said casing with said base, and a stop or fixing-screw connecting the other end of said casing with said base whereby said casing is fixed in its correct closed position about said bush and may be opened out on the hinge-bolt in said base to afford access to said bearing-piece, the readjustment to the exact axial center being effected by the closing of the casing.

10 2. A casing for shaft-bearings consisting of segmental clamps *p* and *q* hinged together, a bearing-piece or race-ring bush, a base, a hinge-joint connecting clamp *p* with said base, a slotted shoe-shaped piece on clamp *q*,

a fixing-screw *c*, and a stop *k*, whereby said casing is fixed in its correct closed position about said bush and may be opened out on the hinge-bolt in said base to afford access to said bearing-piece, the readjustment to the exact axial center being effected by the closing of the casing.

In witness whereof I have hereunto set my hand in presence of two witnesses.

AUGUST RIEBE.

Witnesses:
